[57] CLAIM

The ornamental design of a grass catcher, as shown and described.

DESCRIPTION

FIG. 1 is a perspective view of a grass catcher showing my new design;

FIG. 2 is a top plan view thereof;

FIG. 3 is a side elevational view taken from the left of FIG. 1;

FIG. 4 is a front end elevational view thereof;

FIG. 5 is a side elevational view taken from the right of FIG. 1;

FIG. 6 is a rear end elevational view thereof;

FIG. 7 is a bottom plan view thereof;

FIG. 8 is a perspective view with grass catcher shown in open condition.

FIG. 5

FIG. 6

FIG. 7

FIG. 8
